UNITED STATES PATENT OFFICE.

HERBERT MORRIS PILKINGTON, OF ARVERNE, NEW YORK, ASSIGNOR, BY MESNE ASSIGNMENTS, TO LITHOTEX CORPORATION, OF NEW YORK, N. Y., A CORPORATION OF NEW YORK.

METHOD OF SETTING STEP AND REPEAT MACHINES.

1,131,632.

Specification of Letters Patent.

Patented Mar. 9, 1915.

No Drawing.

Application filed March 5, 1913. Serial No. 752,232.

To all whom it may concern:

Be it known that I, HERBERT MORRIS PILKINGTON, a citizen of the United States, and a resident of Arverne, Long Island, county of Queens, and State of New York, have invented a certain new and useful Improvements in Methods of Setting Step and Repeat Machines, of which the following is a specification.

10 This invention relates to a method of setting a step and repeat machine, and more particularly to the setting of a step and repeat machine for photographically reproducing a design formed on a photographic plate a number of times upon a larger plate or surface so that the reproductions of the design on said last surface shall register exactly with corresponding reproductions of the same design or a component design 20 formed on a previously made photographic plate.

The invention is especially useful in forming plates for making multiple color prints, etc., where one plate for each color has to 25 be made, each plate bearing a number of reproductions of the component unit for that color. In producing photographic plates for multiple color work in step and repeat machines, a separate unit photographic 30 plate or object is made of that part of the design appearing in each of the different colors, and each unit plate is then put in the step and repeat machine and photographed a number of times on a separate large sensitized surface, preferably a glass plate, so as to produce a plate corresponding to each of the colors, each containing a number of reproductions of the unit design corresponding to the color which is to be printed from 40 that plate or from printing surfaces made from that plate.

In order that the different colors will fall in their proper place in the completed print to give the desired registration, it is essential 45 that the reproductions upon the different plates exactly coincide or register as to size and angular position, and in spacing from center to center of the different reproductions. In order that these requirements 50 may be attained, the machine must have exactly the same setting in producing each of the plates corresponding to the dif-

ferent colors. If the unit for one color plate is of slightly different size from the unit or units for the other color plate or plates, 55 or if the focus of the machine has been changed so as to alter in the slightest degree the size of the projected image upon any of the plates to be produced, or if the position of the unit photographic plate or object corresponding to any color has not been adjusted in its holder on the machine so that its projected images on the plate to be produced will have the same relative angular 60 positions as the designs reproduced on the previously made plate corresponding to another color, or if the mechanism for moving the plate step by step past the lens and unit photographic plate has been disturbed since the previous plate was produced, the reproduction on the different plates will not register so as to have the component parts of the completed design properly match. It is, therefore, very important for the operator to determine at the start, that the images 75 of the designs corresponding to any particular color and about to be projected upon the plate will exactly coincide with the reproductions on a previously made plate corresponding to another color.

The present invention is for a method of ascertaining whether, or when, the apparatus is correctly adjusted for size and angular position of the image, or spacing of each design, or any two or more of these 80 data combined, and it consists in placing a developed plate bearing reproductions of the same design or of a component design, in the plane to be occupied by the sensitized surface upon which it is desired to reproduce the unit design or object by means of the step and repeat machine, and projecting an image from the object plate from which the new series of designs is to be formed, onto one of the designs of said previously 85 developed photographic plate with which the new design is to register, and adjusting the machine until the image exactly registers upon the said design on the plate; and if it is desired to check or reset the machine 90 for spacing the designs on the new plate, then shifting the plate transverse to the line of projection to bring the image into registration with the next adjacent design or

designs on the already developed plate to determine the necessary distance through which the plate must be stepped vertically or horizontally between exposures. The 5 apparatus employed for producing these designs may be such as described in British Letters Patent No. 13517 of 1912 for step and repeat machine.

- By my present invention, the operator 10 may quickly and accurately determine what the actual adjustment of his machine is, as to size and angular position of the image and as to the spacing between the images to be projected. To do this he places the 15 object or design to be reproduced in the object holder of the step and repeat machine behind the lens, and places one of the photographic plates previously formed and developed (upon the carriage of the step and 20 repeat machine for holding the sensitized plate which is in front of the lens), in the vertical plane to be occupied by the sensitized plate upon which the object or design now in the machine is to be reproduced. 25 and then he projects the image from this object or unit design onto one of the corresponding designs of the previously made plate now on the plate carriage of the machine. If these exactly coincide, he knows 30 his machine is properly set, and if there is not coincidence between the image and the already developed design, he can adjust the machine and readily see when the adjustment is such that precise registration occurs. 35 This he does by shifting the focusing mechanism, fully set forth in the above-mentioned patent, so as to increase or decrease the size of the image of the design to be reproduced, and if it is found necessary to 40 adjust the angular position of the image with respect to the design on the plate in order to make it coincide therewith, he only has to shift the unit design holder, as shown in said specification, until the image thus 45 projected coincides exactly with the developed design on the plate. If the operator is uncertain about the adjustment of the mechanism for stepping the plate past the lens and unit design, after he has projected the image upon one of the developed 50 designs so that they exactly coincide, he has only to shift the large plate in its plane transverse to the lens until the image coincides with the next developed design on the 55 plate in the same horizontal row, whereupon, by the mechanism shown in the above-mentioned specification, he notes the necessary movement to bring the image into registration with the second design on the plate, 60 and if it is found that the movement does not correspond to his present setting of the machine, he adjusts his machine accordingly, and likewise for determining vertical stepping. The operator in this way can, before 65 he commences the operation of reproducing the design upon the sensitized plate, be absolutely certain that the machine is properly adjusted for executing the second plate, and if any error is found, he can correct it before he has proceeded to make any exposures 70 on the new sensitized plate, and so on with succeeding plates of the series.
- Having now particularly described and ascertained the nature of my said invention and in what manner the same is to be performed, I declare that what I claim is:
1. The method of setting a step and repeat machine embodying a lens, an object holder and a holder for a sensitized plate to be used for photographically reproducing a component unit of a multiple color design a number of times upon a sensitized surface to be used for making a printing plate for one of the component colors of the design, which consists in projecting an image of the 85 unit transparency onto one of the designs of an already made photographic plate for one of the component colors of said design, the plate being placed in the vertical plane to be occupied by the sensitized surface upon 90 which the unit design is to be reproduced, and adjusting the machine until the image exactly falls upon and coincides with said design on the plate.
  2. The method of setting a step and repeat machine embodying a lens, an object holder and a holder for a sensitized plate to be used for photographically reproducing a unit design a number of times upon a sensitized surface which is to be used for 100 making prints of the design, each having a definite relation as to size, angular position and spacing, with designs formed upon a previously made plate, which consists in projecting an image of the unit design or object to be reproduced onto one of a number of corresponding designs on the already made photographic plate placed in the vertical plane to be occupied by the sensitized surface upon which the unit design is to be 110 reproduced, and adjusting the machine until the image exactly falls upon or coincides with said design on the plate.
  3. The method of setting a step and repeat machine embodying a lens, an object 115 holder and a holder for a sensitized plate to be used for photographically reproducing a unit design a number of times upon a sensitized surface which is to be used for making prints of the design, each having 120 a definite relation as to size, angular position and spacing, with designs formed upon a previously made plate, which consists in projecting an image of the unit design or object to be reproduced onto one of a number of corresponding designs on the already made photographic plate placed in the vertical plane to be occupied by the sensitized surface upon which the unit design is to be 125 reproduced, adjusting the machine until the 130

image exactly falls upon or coincides with said design on the plate, and then shifting the plate transverse to the line of projection until the image falls upon and registers with 5 another of said designs on the already made plate, and noting the distance through which the plate was shifted.

In testimony whereof, I have signed my name to this specification, in the presence of two subscribing witnesses.

HERBERT MORRIS PILKINGTON.
